PRESSURE CONTROL VALVE

Herman Albertine, Rutherford, N. J., assignor to
 Rogers Products Company, Inc., a corporation
 of New Jersey

Application July 14, 1930. Serial No. 467,739

4 Claims. (Cl. 251—134)

This invention relates to a new and improved valve construction and more particularly to a hand control valve for high pressure systems.

The present invention is particularly adapted to a lubricating system and provides a control valve which can be very easily manipulated to permit the passage therethrough of grease or other plastic or fluid medium under high pressure.

10 The invention also provides a new and improved arrangement of parts for a hand control valve whereby the normal holding position of said valve permits the outlet thereof to be conveniently attached to a connection leading into the parts to be lubricated.

In accordance with a concrete exemplification of the present invention, the internal valve elements of the control valve are held in selective positions by means of a control lever having the operating end thereof pivotally mounted to the free end of a swingable link and having at this pivoted end a projecting member adapted to actuate said valve elements. This lever is fulcrumed on a resiliently mounted rod, and the parts are arranged so that when the handle of said lever is manipulated the projecting member and the link become substantially aligned with the internal elements of the valve. The pressure of the material in the valve is transmitted through these internal elements to the projecting member. The pressure upon this member is in turn transmitted along the length of the aligned link so that only a negligible resultant of the pressure takes effect upon the manipulated portion of the control lever. Under these conditions, very little force is required to open the valve and still less to maintain the control lever in actuated position. The manipulating pressure is about that required to compress the spring that urges the fulcrum rod toward its normal position.

The invention also consists in certain new and original features of construction and combinations of parts hereinafter set forth and claimed.

45 Although the novel features which are believed to be characteristic of this invention will be particularly pointed out in the appended claims, the invention itself, as to its objects and advantages, the mode of its operation and the manner of its organization may be better understood by referring to the following description taken in connection with the accompanying drawing forming a part thereof, in which

Fig. 1 is a side elevation of the control valve;
 50 Fig. 2 is a left side elevation; and

Fig. 3 is an elevational section. Like reference characters denote like parts in the several figures of the drawing.

In the following description and in the claims, parts will be identified by specific names for convenience, but they are intended to be as generic in their application to similar parts as the art will permit.

Referring particularly to the accompanying drawing, in which a specific embodiment of the invention is shown, there is provided a valve casing 10 having an inlet conduit 11, a parallel offset outlet conduit 12, and a transverse, interposed valve chamber 13. Leading into the discharge outlet conduit 12 is a suitable air relief valve 14 and pivotally mounted on the casing 10 by means of pivot pins 15 are two swingable links 16 the top free ends of which are pivotally mounted on a control lever 17.

In order to provide means for fulcruming the lever 17, the casing 10 is provided with a boss 18 having a bore 19 therethrough for the reception of a slidably mounted rod 20, on one end of which is pivotally mounted the fulcrum of the lever 17. Secured to the other end of this rod is a collar 21 which acts to limit the upward movement of said rod. Secured to said collar 21 is a guide pin 22 encircled by a coil spring 23, which serves to normally urge the rod 20 in its uppermost position.

The end of the lever 17 is provided with a projecting member in the form of an abutment screw 25 which passes through said lever, and which preferably has a smooth rounded portion 26 bearing upon the upper end of a slidably valve actuating element. The latter includes a plunger 27, one end of which has a threaded engagement with one end of a pin 28, the other end of said pin engaging a ball valve 30. This ball is arranged as a check valve normally engaging a valve seat 31, and is urged to closed position by the pressure of the fluid to be controlled and by a coil spring 32. Interposed between the plunger 27 and the pin 28 is a leather cup washer 33 which is adapted to obviate the leakage of the grease through the side of the plunger 27. Access to these valve elements can be obtained by removing a plug 35 screwed into the end of the valve chamber 13.

In the operation of this device, depression of the shank portion 34 of the central lever 17 forces the plunger 20 downwardly against the action of the spring 23 and plunger 27 downward against the pressure of the grease or other fluid. When in this position, the abutment screw 25 will be shifted into a substantially vertical position, and the plunger 27 and the pin 28 will

- be sufficiently depressed to disengage the ball 30 from contact with its valve seat 31, thereby permitting the grease to pass through the valve. When in this open position, the shutoff screw 5 25 will be substantially in the same plane with the plunger 27 and both sets of pivots 15, 15a and the force exerted by the grease on these valve elements will be carried by said links as a pure tension force, while the unbalanced upward thrust of spring 23 will be largely taken care of by friction of the movable parts, the remnant being only that necessary to lift lever 34, when the grip of the operator is relaxed. By means of this arrangement, the lever 17 is kept in an open position against the action of the spring 23 only, the rotational pressure influences exerted on said lever as a result of the internal valve pressure being resisted totally by the tensioned links 16.
- It should also be noted that the inlet and outlet conduits are in substantially parallel axial relationship. By means of this arrangement, when the inlet conduit 11 and the shank 34 of the control lever are grasped into a holding position, the outlet conduit 12 will extend in a direction to permit its convenient attachment to a connection leading into the parts to be lubricated.
- Although the invention has been described with particular reference to its adaptation to a lubricating system, it is obvious that it can be adapted to the outlet control of any pressure system without departing from the spirit of the invention.
- While certain novel features of the invention have been shown and described and are pointed out in the annexed claims, it will be understood that various omissions, substitutions and changes in the forms and details of the device illustrated and in its operation may be made by those skilled in the art without departing from the spirit of the invention.
- I claim:
1. A valve including a valve casing, a valve element therein, a control lever having the operating end thereof cooperating with said valve element, and the medial portion thereof yieldably fulcrumed, means responsive to the actuation of said control lever about its yieldable fulcrum for shifting said valve elements into an open position, a pair of swingable links having one end thereof pivoted to said casing and the other end pivotally connected to the operating end of said control lever, said links being mounted so as to be shiftable into a position substantially aligned with the line of movement of said valve elements.
  2. A valve including a valve casing, a valve element therein, a control lever having the operating end thereof cooperating with said valve element, a rod pivotally mounted at the fulcrum point of said lever, means for guiding said rod in one direction, resilient means for urging said rod to a normal valve closing position, means responsive to the actuation of said control lever about its fulcrum for shifting said valve elements into an open position, and means for withstanding the effect of the internal pressure of the valve so that said pressure will not affect the force necessary to maintain said control lever in an open position.
  3. A valve including a valve casing, a valve element therein, a control lever having the operating end thereof cooperating with said valve element, a rod pivotally mounted at the fulcrum point of said lever, means for guiding said rod in one direction, resilient means for urging said rod in a normal valve closing position, means responsive to the actuation of said control lever about its fulcrum point for shifting said valve elements into an open position, and means whereby said control lever is maintained in closed position substantially against the actuation of said resilient means.
  4. A valve including a valve casing, a valve element therein, a control lever having the operating end thereof cooperating with said valve element, a rod pivotally mounted at the fulcrum point of said lever, means for guiding said rod in one direction, resilient means for urging said rod in a normal valve closing position, means responsive to the actuation of said control lever about its fulcrum point for shifting said valve elements into an open position, a pair of swingable links having one end thereof pivoted to said casing, and the other end pivotally connected to the operating end of said control lever, said links being mounted so as to be shiftable into a position to withstand the internal pressure of the valve when said control lever is actuated whereby said internal pressure does not affect the force necessary to maintain said control lever in an open position.
